[57] ABSTRACT

Novel conjugated enzyme compositions are provided for use in homogeneous enzyme immunoassays. A wide variety of haptic compounds, particularly drugs of abuse, and drugs used in repetitive therapeutic applications, and steroids are conjugated to glucose-6-phosphate dehydrogenase. The resulting product has a higher turnover rate, so as to provide a high multiplication factor when employed in a homogeneous enzyme immunoassay.

ENZYME IMMUNOASSAYS WITH
GLUCOSE-6-PHOSPHATE DEHYDROGENASECROSS REFERENCE TO RELATED
APPLICATIONS

This application is a continuation-in-part of application Ser. No. 304,157, filed Nov. 6, 1972, which is in turn a continuation-in-part of application Ser. No. 143,609, filed May 14, 1971, now abandoned.

BACKGROUND OF THE INVENTION

1. Field of the Invention

Immunoassays have shown themselves to be extremely versatile in allowing for methods to determine the presence of a particular substance, even when a wide variety of other materials of similar or different structure are present in the unknown sample. The immunoassays rely on the ability of an antibody to specifically detect or bind to an haptic organic compound, while not interacting with other compounds. The divalent nature of the antibody and its high molecular weight, 150,000 or greater, allow for a sufficient change in the compound or environment of the compound to permit a discrimination between a compound which is bound and a compound which is not bound to antibody. Among various immunoassays involving antibodies are radioimmunoassay, spin immunoassays, available under the trademark FRAT, supplied by Syva Company, homogeneous enzyme immunoassay, available under the trademark EMIT, supplied by Syva Company, and hemeagglutination.

The enzyme immunoassay is extremely versatile in permitting spectrophotometric determinations. The immunoassay employs an enzyme to which the organic compound to be determined is conjugated. The organic compound is conjugated at a position where when bound to antibody, the activity of the enzyme is substantially reduced. To the extent that the unknown sample contains the same organic compound, the amount of antibody available for binding to the organic compound conjugated to the enzyme is reduced. Therefore, by analyzing for enzymatic activity, a significant increase in enzymatic activity over the enzymatic activity in the absence of the unknown indicates the presence of the organic compound in the unknown.

The sensitivity of the homogeneous enzyme immunoassay is based to a substantial degree on the activity of the enzyme when conjugated and the degree of inhibitory when antibody is bound to the organic compound conjugated to the enzyme. It is, therefore, desirable to have an enzyme which not only has a high turnover rate initially, but retains a substantial proportion of this turnover rate after conjugation, and is strongly inhibited when antibody is bound to the organic compound which is conjugated to the enzyme. Also, the enzyme should allow for strong specific binding of antibody to the conjugated organic compound.

2. Description of the Prior Art

An homogeneous enzyme immunoassay system has been sold under the trademark EMIT employing haptens conjugated to lysozyme, where the enzymatic activity is determined by the reduction in turbidity as a result of lysis of bacterial walls. Numerous publications concerning the system have issued since June of 1971, see for example, Rubenstein, et al., *Biochem & Biophysical Res. Comm.* 47 846 (1972). U.S. Pat. No. 3,654,090 teaches a heterogeneous immunoassay em-

ploying such enzymes as peroxidase and amyloglucosidase.

SUMMARY OF THE INVENTION

5 Haptenic conjugates to glucose-6-phosphate dehydrogenase are provided for employment in homogeneous enzyme immunoassays to provide high sensitivity in detecting extremely small amounts of organic materials. One or more of the haptens (hereinafter referred to as ligands) are conjugated by relatively short chains or linking groups to the glucose-6-phosphate dehydrogenase to provide a product still retaining a substantial proportion of the original enzyme activity and having a high degree of inhibitory, usually in excess of 50% of the original activity of the conjugated glucose-6-phosphate dehydrogenase. The linking chains normally employ a non-oxocarbonyl group or a covalent bond to saturated carbon as the linking group to the enzyme.

20 DESCRIPTION OF THE SPECIFIC EMBODIMENTS

Haptenic conjugated glucose-6-phosphate dehydrogenase is provided having from about 1 to 18, usually from about 2 to 14, and more usually from about 2 to 12 ligands, normally the majority or all of the ligands 25 being bonded to amino groups, particularly of lysine. The haptens or ligands will normally have molecular weights of at least 125 and generally not exceeding 1,000, more usually not exceeding 800, and frequently not exceeding 600 molecular weight. The ligands will have at least one heteroatom and may have two or more heteroatoms, which will normally be oxygen, nitrogen and sulfur, although halogen, particularly chlorine and iodine may also be present. The ligands for the most part will be naturally occurring, physiologically active compounds and synthetic drugs, which will be modified to the extent necessary for conjugation to the glucose-6-phosphate dehydrogenase.

The enzyme conjugates of this invention will for the most part have the following formula:

wherein:

G-6-PDH intends glucose-6-phosphate dehydrogenase;

n indicates the average number of groups bonded to the G-6-PDH and will generally be in the range of 1 to 18, more usually in the range of 2 to 14, and particularly in the range of 2 to 12;

50 R is a bond or a hydrocarbon (aliphatic, alicyclic or aromatic), particularly aliphatic, linking group, either branched or straight chain, of from 0 to 1 rings and of from 1 to 8 carbon atoms, more usually of from 1 to 6 carbon atoms, and preferably of from 1 to 4 carbon atoms, usually having from 0 to 1 site of aliphatic unsaturation, and more usually aliphatically saturated, or substituted hydrocarbon group having from 0 to 3 heteroatoms, more usually 0 to 2 heteroatoms, which are oxygen, sulfur and nitrogen, more usually oxygen and nitrogen (atomic number 7-8); and

55 Y is a ligand of at least 125 molecular weight, usually not greater than 1,000 molecular weight, more usually not greater than 800 molecular weight, and generally not exceeding 600 molecular weight, and has at least one common epitope to a naturally occurring physiologically active compound or synthetic drug, usually differing from the naturally oc-

curring physiologically active compound or synthetic drug by replacement of a hydrogen or modification of a functionality such as an olefin, oxo or the like, to provide a site for bonding of R to the ligand; and

X is a bond, a non-oxocarbonyl group, including the nitrogen and sulfur analogs thereof, i.e. imino and thiocarbonyl, or diazo when R is arylene, aralkylene or a bond and the nitrogen of the diazo group is bonded to an aromatic annular carbon atom.

X may be bonded to R through carbon or a heteroatom, particularly nitrogen. Since sulfur bonds and certain oxygen bonds, e.g. esters will tend to be reactive, these will usually be avoided. Oxygen will normally be present in the linking group as a carbonyl (oxo or non-oxo) or oxyether. Sulfur will normally be present in the linking group as thiocarbonyl or thioether. Nitrogen will normally be present in the linking group as tertiary or quaternary amino, diazo or bonded to a non-oxocarbonyl, including the amino and thioanalogs thereof.

Usually, when R is aromatic (aromatic includes arylene, aralkylene or alkarylene), R will be bonded to Y through a heteroatom, particularly ethereal oxygen, i.e. oxy. R groups of particular interest are methylene or polymethylene, i.e. $(CH_2)_p$, where p is an integer in the range of 1 to 6, alkyleneoxyalkylene, i.e. $(CH_2)_qO(CH_2)_r$, where q and r are the same or different and are integers in the range of 1 to 3, there being at least two methylene groups between heteroatoms, or $(CH_2)_sNH$, where s is an integer in the range of 1 to 6, usually 1 to 4, there being at least two methylene groups between heteroatoms.

When X is other than a bond, X will normally have one of the following formulae:

and will preferably be either the oxygen or the imino non-oxocarbonyl.

The groups for $-\text{R}-\text{X}-$ will include ethylene, propylene, butylene, hexylene, phenylene, p-benzylidene, α -carboxymethylene, carbamoylmethylene ($-\text{NHCOCH}_2-$), iminoxyacetyl ($=\text{NOCH}_2\text{CO}-$), thioacetyl, p-oxybenzyl, maleidioyl, succindioyl, oxo-ethylene ($-\text{OCCH}_2-$), 1-oxobutylene ($-\text{OCCH}_2\text{CH}_2\text{CH}_2-$), ethyleneoxyacetyl, propyleneoxyacetyl, N-methyl 3-aza-1-imino-pentylene ($-(\text{NH}=\text{C})-\text{CH}_2\text{N}(\text{CH}_3)\text{CH}_2\text{CH}_2\text{CH}_2-$), ethylenecarbamoyl ($-(\text{O}=\text{C})\text{NHCH}_2\text{CH}_2-$), propylenethiocarbamoyl ($-(\text{S}-\text{C})\text{NHCH}_2\text{CH}_2\text{C}-\text{H}_2-$), ethyleneoxyacetimidate, ethyleneoxyethylene-thiocarbamoyl, propyleneoxypropylenecarbamoyl and diethyleneoxyacetimidoyl.

Turning now to consideration of individual compounds, the first group of compounds are the alkaloids. Of particular interest among the alkaloids are the opiate alkaloids which will have for the most part the following formula:

isoamyl, allyl, hexyl, Δ^1 -cyclohexenyl and phenyl, and when m is 0 phenyl; one of W and W^1 is $-R^2-X^2-$ and the other is hydrogen.

Z is oxygen, with the proviso that Z may be H_2 when one of T^1 and T^2 is phenyl, e.g. primidone.

m is 0 when the compound is diphenylhydantoin, and 1 when the compound is a barbiturate or Z is H_2 ;

R^2 may be the same as R but is usually an aliphatic group of from 1 to 8 carbon atoms, usually of from 1 to 6 carbon atoms, and preferably of from 1 to 4 carbon atoms, and from 0 to 3 heteroatoms, usually of from 0 to 2 heteroatoms, and from 0 to 1 site of aliphatic unsaturation, where the heteroatoms are oxygen, sulfur and nitrogen, usually oxygen and nitrogen, R^2 being bonded to nitrogen through an aliphatically saturated carbon atom and to X^2 with other than oxygen and sulfur; or aromatic hydrocarbon of from 6 to 9 carbon atoms; and

X^2 is a bond, non-oxocarbonyl including the nitrogen and thioanalogs thereof, or diazo when bonded to an aromatic annular carbon atom.

Illustrative groups for $-R^2-X^2-$ include diazo, methylene, ethylene, butylene, ethyleneoxyethyl, acetyl, imidoylmethyl, propyleneoxyacetimidoyl, carboxyvinylene, carboxypropylene, imidoylbutylene, N-methyl ethyleneaminoethyl, N-methyl ethyleneaminoacetyl, and 1-(1-carboxyethylene).

The next group of compounds are the steroids, which include the estrogens, gestogens, androgens, adrenocortical hormones (glucocorticoids and mineral corticoids and bile acids). Of particular interest are the sex hormones and the adrenocortical hormones. The steroids will be divided into two groups depending on whether the A ring is aromatic or cycloaliphatic.

For the most part, those compounds which are gestogens, androgens, or adrenocortical hormones will come within the following formula:

wherein:

one of Z^1 , Z^2 , and Z^3 is $-R^3-X^3-$, wherein the R^3 may be singly or doubly bonded to the annular carbon atom. R^3 may be the same as R , but is usually an aliphatic group having from 0 to 1 site of aliphatic unsaturation and of from 1 to 8 carbon atoms, usually of from 1 to 6 carbon atoms, and more usually of from 1 to 4 carbon atoms, having from 0 to 3 heteroatoms which are oxygen, nitrogen and sulfur, usually oxygen and nitrogen, R^3 being bonded to X^3 at other than oxygen and sulfur; or aromatic hydrocarbon of from 6 to 8 carbon atoms;

X^3 is a bond, non-oxocarbonyl including the nitrogen and sulfur analogs thereof, or diazo, when bonded to an aromatic annular carbon atom;

when other than $-R^3-X^3-$, Z^2 and Z^3 are hydrogen;

when the compound is a gestogen, there is from 0 to 1 site of ethylenic unsaturation in the Δ^4 or Δ^5 position, and when other than $-R^3-X^3$, Z^1 is hydroxyl or oxo;

Y^1 is acetyl; and

Y^2 and Y^3 are hydrogen;

when the compound is an androgen, when other than $-R^3-X^3$, Z^1 is oxo;

Y^1 is hydroxyl; and

Y^2 and Y^3 are hydrogen;

when the compound is an adrenocortical hormone:

when other than $-R^3-X^3$, Z^1 is oxo;

Y^1 is hydroxyacetyl;

Y^2 is hydrogen or hydroxyl; and

Y^3 is hydroxy or oxo;

n^3 on the average will be in the range of 1 to 14, usually 1 to 12, more usually in the range of 2 to 12.

When the compound is an estrogen and the A ring is aromatic, the compounds will for the most part have the following formula:

wherein:

one of Z^4 , Z^5 , and Z^6 is $-R^4-X^4-$, wherein when Z^4 or Z^6 is $-R^4-X^4-$, R^4 may be singly or doubly bonded to the annular carbon atom, wherein R^4 may be the same as R , but is usually an aliphatic radical having from 0 to 1 site of aliphatic unsaturation and of from 1 to 8 carbon atoms, usually of from 1 to 6 carbon atoms, and more usually of from 1 to 4 carbon atoms and from 0 to 3 heteroatoms which are oxygen, nitrogen and sulfur, more usually oxygen and nitrogen, or aromatic hydrocarbon of from 6 to 8 carbon atoms, and X^4 is non-oxocarbonyl including the nitrogen and sulfur analogs thereof, or diazo when bonded to an aromatic annular carbon atom;

when other than $-R^4-X^4-$, Z^4 , Z^5 and Z^6 will be hydrogen;

Y^4 is hydrogen or hydroxyl; and

n^4 on the average is in the range of from 1 to 14, usually 1 to 12, more usually in the range of from 2 to 12.

Illustrative groups for $-R^3-X^3-$ and $-R^4-X^4-$ include ethylene, ethyleneoxyacetyl, iminoxyacetyl, p-phenylenediazoo, ethylenethiocarbamoyl, carboxybutylene, imidoylpropylene, p-diazobenzyl and thioetheracetyl.

The next compounds are methadone derivatives which will, for the most part, have the following formula:

wherein:

R^5 may be the same as R , but is usually an aliphatic radical of from 1 to 8 carbon atoms, usually of from 1 to 6 carbon atoms, and more usually of from 1 to 4 carbon atoms; and from 0 to 3 heteroatoms which are oxygen, sulfur and nitrogen, particularly oxygen and nitrogen;

X^5 is non-oxocarbonyl including the nitrogen and sulfur analogs thereof; and

n^5 is on the average in the range of from 1 to 14, usually 1 to 12, more usually in the range of from 2 to 12.

The next group of compounds are associated with steroids and are cardiac glycosides of which digoxigenin and digoxin are well known members. For the most part, the compounds will have the following formula:

wherein:

one of Z^7 , Z^8 , and Z^9 is $-R^6-X^6-$, wherein when Z^8 and Z^9 are R^6 , R^6 may be singly or doubly bonded to the annular carbon atoms, wherein R^6 may be the same as R , but is usually an aliphatic radical having from 0 to 1 site of aliphatic unsaturation and of from 1 to 8 carbon atoms, usually of from 1 to 6 carbon atoms, and more usually of from 1 to 4 carbon atoms and from 0 to 3 heteroatoms, usually of from 0 to 2 heteroatoms, which are oxygen, sulfur or nitrogen, preferably oxygen and nitrogen, and X^6 is non-oxocarbonyl including the nitrogen and sulfur analogs thereof, or aromatic hydrocarbon of from 6 to 9 carbon atoms.

when other than $-R^6-X^6-$, Z^7 , Z^8 and Z^9 are hydrogen;

Y^5 is hydrogen or hydroxyl; and

n^6 is on the average in the range of from 1 to 14, usually 1 to 12, more usually in the range of from 2 to 12.

The same groups illustrative of $-R^3-X^3-$ are also illustrative of $-R^6-X^6-$.

While various sources of glucose-6-phosphate dehydrogenase may be employed, a particularly desirable source for the primary use for the subject compounds is the bacterium *L.mesenteroides*. The particular value of the G-6-PDH from this bacterium is that it is able to utilize both NADP and NAD. Since G-6-PDH from animal sources normally is able to utilize only NADP, one can limit interference from endogenous G-6-PDH by employing NAD as the co-factor, when the subject compounds are used in immunoassays.

In preparing the conjugates, it is desirable that at least 20, preferably at least 40 and particularly preferred at least 50% of the original enzyme activity is retained. Furthermore, the enzyme is substituted in such a manner so that when one or more groups are bonded to the enzyme, and are bound by antibody, the activity of the enzyme is reduced by at least 30% of its original activity after conjugation, usually at least 40%, and preferably by at least 50%.

Various ways can be employed for conjugating the various compounds or ligands to the glucose-6-phosphate dehydrogenase. The conditions employed will normally reflect the particular functionality which is employed in forming a bond to the glucose-6-phosphate dehydrogenase. The functionalities which find primary use are the mixed anhydride employing an alkyl chloroformate, acyl azide, the imidate ester, thioimidate, isothiocyanate, reductive alkylation with an aldehyde, or an isocyanate. Normally, the groups will be bonded to available amino groups of lysine as the major mode of conjugation, and therefore amides, amidines, ureas, thioureas, and alkylamines will be formed.

The reaction mixture will normally be buffered to a pH in the range of 5 to 10, more usually in the range of 6 to 9. Various buffers may be used, such as phosphate, carbonate, Tris, and the like. An aqueous solvent will normally be used, and a preferred solvent includes from about 10 to 40 weight percent of an oxyethylene alcohol or ether having from 1 to 3 oxyethylene units. Particularly useful is carbitol. The temperatures will normally be at or above -5°C and generally less than about 40°C , usually from about 0° to 25°C .

The concentration of the enzyme will vary widely, generally ranging from about 0.05 to 5, more usually from about 0.1 to 10mg/ml. The amount of ligand to be conjugated will vary, depending on the ligand enzyme ratio which is desired.

EXPERIMENTAL

The following examples are offered by way of illustration and not by way of limitation.

(All temperatures not otherwise indicated are in centigrade).

EXAMPLE I

A survey was carried out employing the isobutyl chloroformate mixed anhydride of O^3 -carboxymethylmorphine and methyl O^3 -morphinoxyacetimidate.

The conjugations were carried out as follows. The enzyme was obtained as a 4.8 mg/ml solution in 30% glycerol. Specific activity was 561 IU/mg protein for NAD reduction at 30° . The glycerol solution was dialyzed

against 0.05M sodium phosphate, pH 7.5 and diluted with that buffer to a concentration of 2 mg/ml. The pH was adjusted to 7.0 with 1M HCl. To one ml of this cooled (4°) stirred enzyme solution was added in five portions during 5 minutes, 37.5 μ l of a 0.2M solution of the mixed anhydride (N-methyl-¹⁴C) in dimethylformamide. After each addition, the pH rose slightly and was readjusted to 7 with 1M HCl. The solution was then maintained for 5 hours at 4° and dialyzed exhaustively against 0.55M Tris-HCl, pH 7.9. The resulting solution was diluted to 2ml with dialysis buffer. Scintillation counting was then employed to determine the number of ligands conjugated to the enzyme on the average.

To determine the activity of the enzyme and its inhibition, immunoassays were carried out. The assay mixture had a total volume of 1ml and was prepared from 20 μ l of 0.1M NAD in water (pH 5-6), 50 μ l of 0.066M glucose-6-phosphate in assay buffer, and enzyme solution. The remaining volume was made up by the assay buffer which was 0.055M Tris-HCl, pH 7.9. The mixture was incubated for 60 seconds in a spectrophotometer flow cell at 30°, and the increase in absorbance at 350nm was then read over a 1 minute interval. 10 μ l of the above enzyme solution diluted 1:100 in assay buffer containing 0.1% RSA (rabbit serum albumin) gave a rate of 0.160 optical density units per min. (OD/min.). This corresponded to 52% of the activity of the native enzyme. Addition of a large excess of an antiopiate gamma-globulin preparation (5 μ l of a solution that was 8×10^{-5} M in binding sites) prior to addition of the enzyme solution to the assay mixture reduced the activity by 78% (0.0350D/min.). When 50 μ l of 10⁻⁴M morphine and water was added to the substrates prior to addition of the antibody and enzyme, the total enzyme activity was recovered.

A number of preparations were carried out using differing buffers, pH's, and mole ratios. Also, in some instances, the enzyme substrates were included to determine their effect on deactivation. It was found that above 14 ligands per enzyme molecule on the average, substantial deactivation of the enzyme had occurred. The following table indicates the results:

EXAMPLE II

A general conjugation procedure was employed as follows: Commercial G-6-PDH 4.9mg/ml (Beckman 10 Microbics) was dialyzed against 0.055M Tris-HCl buffer, pH 7.9. The concentration subsequent to dialysis was adjusted to 2mg/ml or 1×10^{-8} moles of enzyme per milliter. A 0.5ml aliquot of the enzyme solution was placed in a glass vial equipped with a micromagnetic 15 stirring bar and a pH electrode and cooled in an ice bath. To the stirring solution was added 20mg NADH (0.026mmole) and 11mg of glucose-6-phosphate (0.034mmole) as crystalline solids. To the cold stirring solution was added slowly by means of a syringe needle 20 below the liquid surface, sufficient carbitol to provide 25% by volume (approximately 125 μ l). To this solution was then added by means of a syringe, the ligand at approximately 0.1M in carbitol. The reaction mixture was then incubated and aliquots withdrawn, 25 diluted and the rates determined as to deactivation and inhibition.

The assay procedure was as follows. 2 parts of a solution 0.1M NAD in water at pH 5-6 was combined with 3 parts by volume of 0.11M glucose-6-phosphate in 30 0.055M Tris-HCl buffer, pH 7.9. An aliquot from the conjugation reaction mixture was diluted 1:1,000 with the above indicated buffer. An assay solution was formed from 50 μ l of the G-6-P/NAD solution, 750ml of buffer, 50 μ l of buffer or buffer containing 35 antibody, depending on whether the deactivation or inhibitory was being determined, and 50 μ l of the enzyme conjugate or enzyme control. Portions of buffer were employed to insure quantitative transfers. The solution was aspirated into a spectrometer and the rate of 40 NADH production was followed at 340nm at 37°. The change in OD per min. was determined between the second and third minutes.

The following table indicates the results obtained.

ⁱⁱDialyzed against four changes of 0.055M Tris-HCl, pH 7.9.

EXAMPLE III

A number of experiments were carried out following the following procedure. A 500 μ l solution at a concentration of 2mg/ml of G-6-PDH which had been freshly dialyzed in 0.055M Tris buffer, pH 7.9 and then diluted to the indicated concentration was cooled in an ice bath and 100 μ l of the ligand to be conjugated added over a 5 minute period. A syringe was used for the addition of the ligand, with the tip of the syringe kept underneath the surface of the reaction mixture near the stirring bar.

As soon as the addition of the ligand was complete, an aliquot was taken out and diluted 1:1,000 with the above buffer containing 0.1 weight % RSA. Subsequently, additional aliquots were removed and assayed.

The assay procedure was as follows. Approximately, a 10 μ l aliquot of the reaction mixture was added to a 35 0.5ml portion of the buffer containing 0.1 weight % RSA and then further diluted, by taking 20 μ l of this solution and adding it to 0.4ml of the same buffer. This provides a 1:1,000 dilution.

Sufficient buffer was initially added to the cup to provide a final volume of 1ml. To the buffer was then added 70 μ l of 2:3 parts by volume of 0.066M G-6-P in 0.055M Tris, pH 7.9, 50 μ l of stock antimorphine solution and 50 μ l of the above diluted enzyme reaction mixture. The solution was aspirated into a spectrometer and followed at 340nm for the first 40 secs.

The following table indicates the results obtained with a variety of haptens.

EXAMPLE IV

5-(N-Phenobarbityl)pentanoic acid conjugation to glucose-6-phosphate dehydrogenase

A. Into a reaction vessel was introduced 0.5ml of dimethylformamide (DMF), 16.6mg of 5-(N-phenobarbityl)pentanoic acid and 6.95 μ l of triethylamine and cooled to -10° . To the solution was then added 8.5 μ l of carbityl chloroformate, the mixture warmed to 0° and allowed to stand for 45 minutes, at which time it was ready for use.

tion, prepared as described in part (A), and carbonate buffer, using a syringe with the needle below the surface. The reaction was found to occur in less than 30 minutes, although some reaction times were allowed to proceed for as long as 2 hours. At the end of the reaction, any precipitate or cloudiness was substantially removed by centrifugation of the sample. The assay employed followed the procedure described in Example III.

The following table indicates the materials employed and the percent inhibitability of the enzyme conjugate.

TABLE IV

Enzyme ¹ Buffer	Phenobarbityl mixed Anhydride μ l	Carbitol μ l	0.1M aq. carbonate μ l	pH	Time hrs.	P/E ² mole-ratio	D ³	% I ⁴

P phosphate 0.01M, pH

2. P/E — phenobarbital/enzyme

3. deactivation — based on activity of enzyme prior to conjugation.

4. inhibition — based on activity of enzyme in presence of excess of antiphenobarbital as compared to activity of conjugated enzyme

B. Varying ratios of phenobarbital were combined with glucose-6-phosphate dehydrogenase in differing buffers. The following is the general procedure.

Into a reaction vessel was introduced 0.25ml of an aqueous buffered solution containing 0.5mg of glucose-6-phosphate dehydrogenase, 5.23mg of glucose-6-phosphate and 9.9mg of NADH. To the mixture was then added carbitol followed by an aliquot of the solu-

EXAMPLE V

4-(5'-Phenylbarbituryl-5')crotonic acid conjugate to glucose-6-phosphate dehydrogenase

A. Into a reaction flask fitted with a drying tube was introduced 250 μ l of DMF, 15.8mg of 4-(5'-phenylbarbituryl-5') crotonic acid, and 6.8 μ l of triethylamine and cooled to -8° . To the mixture was slowly added

9.3 μ l of carbityl chloroformate while maintained at a temperature of -4°.

B. Two reactions were carried out, each reaction mixture employing one ml of 0.055M tris buffer, pH 7.9, containing 1.55mg of G6PDH, 353 μ l of carbitol, and 25 μ l of 1N sodium hydroxide following the previously described procedure in Example IV. In the first reaction mixture, 25 μ l of the above mixed anhydride was employed, while in the second reaction mixture 29 μ l of the above mixed anhydride was employed. Upon assaying for the enzyme as described previously, the percent deactivation was found to be 69.4 and 69.9 respectively, while the percent inhibition was found to be 74.4 and 75%, respectively.

EXAMPLE VI

5 20 25 30 35 40 45 50 55 60 65 70 75 80 85 90 95 100
5-(N-Diphenylhydantoinyl)pentanoic acid conjugate to glucose-6-phosphate dehydrogenase

A. Into a reaction vessel was introduced 0.125ml DMF 17.8mg of 5-(N-diphenylhydantoinyl)pentanoic acid and 6.8 μ l of triethylamine, the mixture cooled to -10°, and 9.3 μ l of carbityl chloroformate added slowly while maintaining the temperature below 0°.

B. Following the previously described procedure in Example IV, into a reaction flask was introduced 0.595ml of tris buffer, pH 7.9 containing G6PDH at a concentration of 0.955 mg/ml, 5.25mg of glucose-6-phosphate, 9.9mg of NADH and 150 μ l of carbitol, and the pH adjusted to 8.5 with 1N sodium hydroxide. To the mixture was then added 2 μ l of the above mixed anhydride with the pH being brought to 9.5, the total amount of 1N sodium hydroxide added being 116 μ l. The following table indicates the percent deactivation and inhibitory of the resulting product.

TABLE V

2-(N-Diphenylhydantoinyl)ethoxyacetic acid conjugate to glucose-6-phosphate dehydrogenase

A. To a vessel containing 17mg of dried 2-(N-diphenylhydantoinyl)ethoxyacetic acid was added 250mg of dry DMF. To the solution was then added by syringe 9 μ l of triethylamine. After cooling to 0°, 9 μ l of carbityl chloroformate was added by syringe. After stirring for 1 hour at 0°, a white precipitate formed. The supernatant was used as is and was 0.2M in mixed anhydride.

B. To 0.5ml of 0.01M phosphate buffer, pH 8, containing 0.5mg of glucose-6-phosphate dehydrogenase was added 10mg of NADH and 5mg of G-6-P. After cooling in an ice bath, 200 μ l of carbitol (Dowanol-DB)

was added slowly by syringe below the surface of the solution. The pH was monitored and adjusted by the addition of 0.1N sodium carbonate to 9.14. To the solution was then added 15 μ l of the above mixed anhydride solution in the same manner as the carbitol, with the pH dropping to 8.98. After 10 minutes from the addition, the solution was diluted with 1ml Tris-HCl, pH 7.9 buffer and assayed. Following the procedure described previously in Example IV, the percent deactivation was found to be 29, while the percent inhibitory was found to be 47.

EXAMPLE VIII

5 10 15 20 25 30 35 40 45 50 55 60 65 70 75 80 85 90 95 100
2-(N-Diphenylhydantoinyl)propionic acid conjugate to glucose-6-phosphate dehydrogenase

A. To a flask containing 16.2mg of 2-(N-diphenylhydantoinyl)propionic acid was added under nitrogen 250 μ l of DMF and 7.05 μ l of triethylamine. After cooling the mixture to -4°, 9.25 μ l of carbityl chloroformate was added, and the mixture allowed to react at -3° for 1 hour.

B. To 0.5ml of Tris-HCl buffer, pH 7.9, containing 0.732mg of glucose-6-phosphate dehydrogenase, 19.8mg of NADH and 10.5mg of G-6-P was added slowly by syringe below the surface of the reaction mixture, 9.5 μ l of the above prepared mixed anhydride. During the addition, the pH was maintained at 9.0 by the addition of 0.1N NaOH. Employing the procedure described previously in Example IV, the enzyme was then assayed and was shown to be 59% deactivated and 53% inhibitory.

Reagents were prepared as follows. Where the preparation is not available in the literature, an exemplary preparation is provided.

EXAMPLE A

5 10 15 20 25 30 35 40 45 50 55 60 65 70 75 80 85 90 95 100
Carbityl N-phenobarbitylacetimidate

1. To a solution of 2g sodium phenobarbital in 10ml of DMSO, 500 μ l of chloroacetonitrile in 10ml of DMSO was added over a 1-hour period under nitrogen. After stirring for an additional 30 minutes, the mixture was poured into 100ml 5 weight % sodium carbonate and washed with chloroform. The chloroform was washed once with 5 weight % sodium carbonate and the combined carbonate solutions acidified with 6N HCl, followed by extracting three times with chloroform. After drying the combined chloroform extracts, the chloroform was evaporated to leave an oil. The oil was chromatographed on 75g silica gel-HF with 15% ethyl ether in methylene chloride. The fractions containing the product were combined, evaporated, and the residue crystallized from chloroform-hexane to yield 650mg product (30% yield). m.p. 152°-154°.

2. To 2ml of carbitol was added 23mg sodium hydride under nitrogen and the mixture was allowed to stand until the sodium hydride had reacted. To the alkoxide was added 118mg of the above product and the mixture stirred at room temperature under nitrogen for 24 hours.

EXAMPLE B

Carbityl 2-(N-phenobarbityl)ethoxyacetimidate

1. To a solution of 635mg of sodium phenobarbital in 7ml of dry DMSO heated to 60° under nitrogen was added 345 μ l 2-chloroethoxyacetonitrile and 5mg potassium iodide and the mixture stirred overnight under nitrogen at 60°-70°. The reaction mixture was then stripped of volatiles at 60° at 0.2mm Hg, the residue dissolved in ethyl ether and extracted 5 times with 5 weight % sodium carbonate. The alkaline extracts were acidified, extracted three times with ethyl ether and the combined ether extracts washed with brine, dried, and stripped to yield an oil. The oil was purified on preparative TLC with 4:1 ethyl ether: petroleum ether. An oil weighing 237mg was isolated.

2. Into 1ml of carbitol was dissolved 8.5mg of sodium hydride under nitrogen. To the mixture was 42mg of the above product and the mixture allowed to stand for 2 days at room temperature under nitrogen.

EXAMPLE C

Carbityl N-diphenylhydantoinylacetimidate

1. A solution of 500mg of sodium diphenylhydantoin and 415mg of chloroacetonitrile in 20ml of DMF under nitrogen was heated at 40°-50° for 66 hours. At the end of this time, the mixture was evaporated to near dryness, water added and the aqueous solution extracted with chloroform. The chloroform was first washed with water followed by 1N sodium hydroxide and then dried and evaporated. The resulting oil was crystallized from absolute ethanol to yield 255mg. m.p. 125°-7°.

2. Approximately 1mg of sodium hydride was dissolved in 0.5ml carbitol to which was added 25mg of the above product, which was stirred overnight under nitrogen.

EXAMPLE D

Carbityl O³-estradioloxymethylacetimidate

1. To a solution of 1g of estradiol in 40ml of dry acetone was added 0.7ml of chloroacetonitrile and 5g of freshly powdered anhydrous potassium carbonate. The solution was refluxed under nitrogen overnight, filtered, the solids washed with acetone, and the combined acetone fractions evaporated. The residue was dissolved in chloroform, filtered through silica, discarding early fractions which were product free. The remaining fractions were evaporated, the residue taken up in ethyl ether and the resulting crystals isolated. 50 760mg. m.p. 110°-13°. Recrystallization from ethyl ether yielded a product having a m.p. 112°-114°.

2. Into 1ml of carbitol was dissolved 1mg sodium hydride, followed by the addition of 31mg of the above product under nitrogen. The mixture was stirred overnight at room temperature.

EXAMPLE E

Methyl O³-morphinoxyacetthioimidate

1. O³-Cyanomethylmorphine (200mg) was suspended in 2ml of methyl mercaptan. To the mixture was added 3mg sodium hydride, the flask sealed and stirred at room temperature for 24 hours. The mixture was neutralized with 3.5 μ l acetic acid and concentrated in vacuo. The residue was taken up in methylene chloride, filtered through celite and concentrated in vacuo to yield 220mg of a light brown foam.

EXAMPLE F

O³-Isothiocyanatoethylmorphine

5 1. In 10ml of THF freshly distilled from lithium aluminum hydride (LAH) was suspended 400mg of LAH under nitrogen. A solution of 400mg of chloroacetonitrile in 4ml freshly distilled THF was added over 5 minutes, followed by refluxing for 1 hour. The mixture was allowed to cool and 0.6ml water added followed by 0.6ml 10 weight % sodium hydroxide and 2ml of water. After filtering the mixture, the salts were washed with THF, the THF fractions combined, dried with magnesium sulphate under nitrogen, filtered and the filtrate evaporated yielding 380mg of O³-aminoethylmorphine.

10 2. O³-Aminoethylmorphine (200 mg) in 10ml chloroform was added to a solution of thiophosgene (56 μ l) and potassium bicarbonate (482mg) in 55ml water and the mixture stirred for two hours. The phases were separated and the aqueous phase washed twice with chloroform (20ml). The combined chloroform phases were dried by gravity filtration through three thicknesses of chloroform moistened filter paper. The chloroform solution was evaporated yielding 200mg.

EXAMPLE G

O³-Morphinoxyacetaldehyde

1. To 6.06g dry morphine in 40 ml degassed DMSO 30 was added 850mg of 56 weight % sodium hydride in mineral oil and the mixture stirred under nitrogen until hydrogen evolution ceased. Bromoacetaldehyde diethyl acetal (3ml) was then added and the mixture stirred at 60° under nitrogen overnight. The solvent was 35 then removed at 40°, 0.05mm Hg and the residue purified on a 350g silica gel HF-254 column, using 10% methanolchloroform as a solvent. Fractions containing the desired product were collected and the solvent removed yielding 5.35g (67%).

2. Into 80ml of degassed 1N hydrochloric acid was 40 added 5.9g of the above product and the mixture allowed to stand overnight. The solution was then brought up to pH 4.7 by addition of 5N sodium hydroxide and the water removed at 30° at 0.05mm Hg. The 45 residue was dissolved in hot isopropanol and cooled to precipitate NaCl and impurities. The solution was filtered, the filtrate stripped in vacuo and the residue isolated as a glass. The product could not be crystallized and was isolated as a glass.

EXAMPLE H

5-(N-Phenylbarbital)pentanoic acid

55 Into a reaction flask was introduced 48ml of dimethylformamide, 4g of sodio phenobarbital, 3.68g of ethyl 5-bromopentanoate and 0.8g of potassium iodide, the mixture heated to 40°C and then stirred at room temperature overnight. After evaporating to dryness under a high vacuum, the residue was washed with water, followed by dissolving the residue in methylene chloride.

60 The organic phase was then extracted with dilute sodium hydroxide, pH 12, and the alkaline layer acidified with 6N HCl to pH 2. A mixture of starting material and product precipitated out which was chromatographed with 1% methanol in chloroform on 75g silica gel.

65 Of the 1.44g of the product which is obtained from the column, 1.24g was dissolved in a mixture of 25ml

tetrahydrofuran, 25ml of concentrated HCl and 16ml of water, the mixture stirred overnight, followed by evaporation of the THF. After diluting with saturated sodium chloride, the mixture was extracted with methylene chloride, the organic phase isolated and extracted with saturated bicarbonate solution. After acidifying the aqueous phase to pH 3 with concentrated HCl, the aqueous phase was extracted with methylene chloride, washed with water and then evaporated to yield 0.95g. The 0.95g was recrystallized from a mixture of diethyl ether-heptane, to yield 700mg, m.p. 122°-123°.

EXAMPLE I

4-(5'-Phenylbarbituryl-5')crotonic acid

Into a reaction flask was introduced 100mg (0.49mmole) of 5-phenylbarbituric acid, 24mg (0.5mmole) of sodium hydride and 5ml of DMF and the mixture stirred vigorously until a clear solution was obtained. To the mixture was then added 145mg (103 μ l, 0.75mmole) of ethyl 4-bromocrotonate. After stirring the mixture overnight at room temperature, the reaction mixture was evaporated to dryness under high vacuum and the residue partitioned between ethyl acetate and dilute hydrochloric acid. After extracting the aqueous layer with ethyl acetate, the organic layers were combined, and washed twice with water and once with brine, followed by drying over sodium sulphate. The dried solution was then evaporated to dryness, and the residue chromatographed employing a 1:1 benzene-ethyl acetate mixture.

The ester (50mg, 0.16mmole) prepared above was dissolved in 1ml of 1N aqueous sodium hydroxide at room temperature. After about 15 minutes, the mixture was acidified with 6N HCl and the precipitate filtered and dried to give 35mg of a white powder. m.p. 226°-8°.

EXAMPLE J

5-(N-Diphenylhydantoinyl)pentanoic acid

To a stirring suspension of 3.4g of sodio diphenylhydantoin in 20ml of dry DMF was added 2.63g of ethyl 5-bromopentanoate and a trace of potassium iodide. After stirring the mixture overnight at 60°, the solution was diluted with water and extracted with diethylether. After washing the ethereal solution with water, the ethereal solution was dried, filtered and the filtrate evaporated to an oil, which solidified and was recrystallized from aqueous ethanol. Total yield 3.2g.

The ester prepared above (2.0g) was dissolved in 80ml dioxane and 40ml 10 weight % aqueous potassium hydroxide added. The phases separated but stirring was vigorously continued for 10 minutes, at which time additional water was added and a single phase formed. The aqueous solution was extracted with ether three times, acidified and filtered to give 1.5g of acid, which was recrystallized from benzene.

EXAMPLE K

2-(N-Diphenylhydantoinyl)ethoxyacetic acid

Into a reaction flask was introduced 4g of sodio diphenylhydantoin, 3ml of 2-chloroethoxyacetonitrile and 120ml of DMF and the mixture was stirred under nitrogen at 35° for 15 minutes, followed by raising the temperature to 60° and continuing the stirring for an additional 24 hours. After evaporating to dryness, the

residue was taken up in diethylether, and the ethereal solution washed twice with water, once with 0.05N aqueous sodium hydroxide and once with aqueous sodium chloride, followed by drying with magnesium sulphate. The solution was then evaporated, the residue taken up in 60ml ethanol and the solution heated to boiling to yield 3.49g of white crystals. After recrystallizing from ethanol, the product had a m.p. 125°-128°.

Into 15ml of ethanolic 1N sodium hydroxide was introduced 200mg of the above nitrile and the mixture stirred overnight. Water was added, and the ethanol evaporated to yield a clear solution which was acidified to pH 1 with 6N HCl. The precipitate was isolated by filtration to yield 187mg of a white powder. m.p. 160°-168°.

EXAMPLE L

2-(N-Diphenylhydantoinyl)propionic acid

Into a reaction flask was introduced 825mg sodio diphenylhydantoin, 543mg of ethyl 2-bromopropionate, and 10ml of DMF, the mixture heated to 60° under nitrogen and 40mg potassium iodide added to the stirred solution. After heating overnight, the reaction mixture was poured into 25ml of water, the flask washed with water and ether, the liquids combined and extracted twice with a total volume of 100ml of ether, and the ethereal extracts washed three times with a total volume of 75ml of water and once with brine. After evaporating the ether, the solution was flashed with a mixture of benzene, chloroform and ethanol, followed by flashing with carbon tetrachloride to yield an oil. The oil was dissolved in diethyl ether, the ethereal solution washed twice with water (total volume 25ml), dried over sodium sulphate and evaporated to an oil which was flashed with carbon tetrachloride, followed by chloroform, followed by a mixture of benzene and ethanol. The residue was dissolved in hot ethanol, a portion of the ethanol evaporated, and water added to cloud point. Upon standing, an oil formed, which was repeatedly redissolved by repeated reheating and cooling, followed by addition of ethanol, at which time crystals formed which quickly became an oil. Benzene-ethanol was added and the solution evaporated to leave an oil.

Into approximately 12ml of THF and 4ml 1N aqueous sodium hydroxide was dissolved the oil prepared above. The two phase solution was stirred at room temperature for about 60 hours. The THF was then stripped in vacuo, the solution acidified to pH 1 with 6N HCl, at which time a solid formed which was filtered and dried.

The solid was further purified by dissolving in 50ml diethyl ether, the ethereal solution washed with 50ml of saturated bicarbonate, the bicarbonate layer acidified to produce a precipitate which was isolated, extracted three times with diethyl ether for a total volume of 100ml and the diethyl ether evaporated to dryness to yield 673mg. The product could be recrystallized by dissolving in methanol and adding chloroform to the cloud point.

Because of the high turnover rate for the glucose-6-phosphate dehydrogenase, as well as the substantial degree of activity which is retained after conjugation with haptens, highly sensitive assays can be developed for a wide variety of haptens. Of course, the sensitivity of any particular enzyme conjugate in an assay is based on keeping all of the variables constant. Two significant

considerations in an immunoassay are: (1) the lowest concentration level at which the material can be detected with some degree of reliability; and (2) the spread between various concentration levels. In order to evaluate the G-6-PDH assay, standards were prepared having varying concentrations of the drug of interest. The assay was carried out as follows. Serum (50 μ l) containing the drug at the particular concentration was diluted with 250 μ l of buffer, Tris-HCl, pH 8.2 in order to insure quantitative transfer to the cuvette. To the dilute serum was then added 50 μ l of the appropriate antibody at a concentration of about 4-5 $\times$ 10⁻⁸M in binding sites (as determined by FRAT immunoassay, supplied by Syva Company), 0.1M NAD and 0.066M G-6-P. Quantitative transfer was achieved with 250 μ l of buffer. Finally, the appropriate enzyme conjugate was added which had sufficient enzyme to provide an activity in the absence of antibody of 200 Δ OD/min at 340nm in the assay mixture, and the transfer made quantitative with 250 μ l of buffer, to provide a final volume of 0.9ml. The entire mixture was allowed to stand and equilibrate for one minute and the change in optical density read for the second minute at 340nm. The following table indicates the readings for the various standard solutions with different drugs.

TABLE VI

Morphine conc. ng/ml	reading Δ OD/min	Phenobarbital conc. μ g/ml	reading OD/min	Diphenylhydantoin conc. μ g/ml	reading OD/min
0	102	0	140	0	122
1	103	1	151	1	124
5	111	5	163	5	134
10	116	10	170	10	141

It is evident from the above results, that concentrations of a few ng with morphine or a few μ g with phenobarbital and diphenylhydantoin are readily determinable rapidly from serum. It is believed, that further improvement in the assays of the latter two drugs can be achieved with further refinement as to the antibodies. Therefore, the use of glucose-6-phosphate dehydrogenase as the enzyme provides an opportunity for extremely selective and sensitive tests for a wide variety of different drugs having widely varying structures.

The use of glucose-6-phosphate dehydrogenase has many desirable characteristics when employed in an homogeneous enzyme immunoassay. The high turnover rate of the enzyme provides the opportunity for an extremely sensitive test for determining drugs at very low concentration. Furthermore, the enzyme can be conjugated so as to be readily inhibitable, without undesirably high deactivation of the enzyme. Furthermore, the enzyme is relatively stable so it can be prepared as a reagent and stored and shipped. In addition, the enzyme employs a substrate which is colored, having strong absorption in the far ultraviolet region, and therefore can be easily detected in a conventional spectrophotometer.

Although the foregoing invention has been described in some detail by way of illustration and example for purposes of clarity of understanding, it will be obvious that certain changes and modifications may be practiced within the scope of the appended claims.

What is claimed is:

1. An enzyme conjugate of glucose-6-phosphate dehydrogenase of the formula:

G-6-PDH } (X-R-Y)_n

wherein:

G-6-PDH intends glucose-6-phosphate dehydrogenase;

n is the average number of groups bonded to the G-6-PDH and is in the range of 1 to 18;

X is a bond or non-oxocarbonyl, including the nitrogen and sulfur analogs thereof;

R is an aliphatic linking group of from 1 to 8 carbon atoms and 0 to 3 heteroatoms which are oxygen, sulfur, or nitrogen;

Y is a hapten of at least 125 molecular weight and not greater than about 1,000 molecular weight.

2. An enzyme conjugate according to claim 1, wherein n is of from 2 to 12, X is a non-oxocarbonyl group, R is of from 1 to 4 carbon atoms and 0 to 2 heteroatoms, and Y is a hapten of from about 125 to about 650 molecular weight.

3. An enzyme conjugate according to claim 1 wherein said glucose-6-phosphate dehydrogenase is derived from the bacterium *L.mesenteroides*.

4. An enzyme conjugate of the formula:

wherein:

T is hydrogen or acetyl;

n^1 is on the average 1 to 14;

X¹ is a bond, non-oxocarbonyl, including the thio and nitrogen analogs thereof or, when R¹ is aromatic hydrocarbon, diazo; and

R¹ is an aliphatic group of from 1 to 8 carbon atoms and 0 to 3 heteroatoms which are oxygen, sulfur or nitrogen or aromatic hydrocarbon of from 6 to 9 carbon atoms.

5. An enzyme conjugate according to claim 4, wherein X¹ is non-oxocarbonyl, R¹ is a saturated aliphatic group of from 1 to 4 carbon atoms and T is hydrogen.

6. An enzyme conjugate of the formula:

R^5 is an aliphatic radical of from 1 to 8 carbon atoms and from 0 to 3 heteroatoms which are oxygen, sulfur or nitrogen or aromatic hydrocarbon of from 6 to 9 carbon atoms;

X^5 is a bond, non-oxocarbonyl including the nitrogen and sulfur analogs thereof or, when R^5 is aromatic hydrocarbon, diazo; and

n^5 is on the average in the range of from 1 to 14.

14. An enzyme conjugate of the formula:

wherein:

one of Z^7 , Z^8 and Z^9 is R^6-X^6 , wherein when Z^8 or Z^9 is R^6-X^6 , R^6 may be singly or doubly bonded to the annular carbon atoms and is an aliphatic radical of from 1 to 8 carbon atoms and from 0 to 3 heteroatoms which are oxygen, sulfur or nitrogen, or aromatic hydrocarbon of from 6 to 9 carbon atoms;

X^6 is a bond, non-oxocarbonyl including the nitrogen and sulfur analogs thereof or, when R^6 is aromatic

hydrocarbon, diazo; when other than $-R^6-X^6-$, Z^7 , Z^8 and Z^9 are hydrogen;

Y^6 is hydrogen or hydroxyl; and

5 n^7 is on the average in the range of from 1 to 14.

15. A morphine conjugate to glucose-6-phosphate dehydrogenase having from 1 to 14 morphine groups, wherein the morphine is joined at the O^3 position to an acetimidate linking group.

10 16. A morphine conjugate to glucose-6-phosphate dehydrogenase having from 1 to 14 morphine groups, wherein the morphine is joined at the O^3 site to an acetyl linking group.

17. A phenobarbital conjugate to glucose-6-

15 phosphate dehydrogenase having from 1 to 14 phenobarbital groups, wherein the phenobarbital is joined at

the 1 nitrogen position through an acetimidate linking group.

18. A phenobarbital conjugate to glucose-6-

20 phosphate dehydrogenase having from 1 to 14 pheno-

barbital groups wherein the phenobarbital is joined at

the 1 nitrogen position to an ethyleneoxyacetimidate

linking group.

19. A phenobarbital conjugate to glucose-6-

25 phosphate dehydrogenase having from 1 to 14 pheno-

barbital groups wherein the phenobarbital is joined at

the 5 position to a α -crotonyl linking group.

20. A diphenylhydantoin conjugate to glucose-6-

phosphate dehydrogenase having from 1 to 14 diphe-

30 nylhydantoin groups wherein the diphenylhydantoin is

joined at the 3 nitrogen to an acetimidate linking

group.

21. An estradiol conjugate to glucose-6-phosphate

dehydrogenase having from 1 to 14 estradiol groups,

35 wherein the estradiol is joined at the O^3 position to an acetimidate linking group.
